UNITED STATES PATENT OFFICE.

MAX RICHARD LEHMAN, OF QUINCY, ILLINOIS, ASSIGNOR TO THE GLOBE STOVE & RANGE COMPANY, OF KOKOMO, INDIANA.

DESIGN FOR A HEATING-STOVE.

48,556.

Specification for Design.

Patented Feb. 15, 1916.

Application filed November 8, 1915. Serial No. 60,444. Term of patent 3½ years.

To all whom it may concern:

Be it known that I, MAX RICHARD LEHMAN, a citizen of the United States, residing at Quincy, in the county of Adams, State of Illinois, have invented a new, original, and ornamental Design for a Heating-Stove, of which the following is a specification, reference being had to the accompanying drawing, forming a part thereof.

Figure I is a front elevation of a heating

stove showing my new design. Fig. II is a side elevation thereof.

I claim:

The ornamental design for a heating stove, as shown.

MAX RICHARD LEHMAN.

Witnesses:

MICHAEL REINERT,
EDWIN C. BUERKIN.
